UNITED STATES PATENT OFFICE.

JOSEPH L. BARTH, OF BISMARCK, NORTH DAKOTA.

METATARSAL PAD LOCATOR.

Application filed April 29, 1924. Serial No. 709,875.

The present invention is primarily designed to enable an imprint of the human foot to be taken, so as to show the location of the metatarsal heads, said imprint being used as a basis for the measurements in making a shoe to fit the foot.

Another object is to provide a novel construction wherein the measurements may be made along the arch of the foot or curved 10 surface as contrasted with a flat or straight surface.

Another object is to provide a construction wherein the measurements along a curved surface or along a straight surface 15 may be selectively made.

Another object is to provide a novel construction of arch, particularly one which is adjustable to the arch of the shoe, and particularly in which the adjustable part may 20 be moved to different extents through manipulation of a single element and according to the arch of that shoe in which the pad is to be placed.

Additional objects and advantages will 25 become apparent from a consideration of the description following taken in connection with accompanying drawings illustrating an operative embodiment, in which:

Figure 1 is a plan view with the adjustable arch device removed;

Figure 2 is a substantially central longitudinal sectional view through the device complete;

Figure 3 is a plan view of the adjustable arch device;

Figure 4 is a substantially central longitudinal sectional view through the adjustable arch device;

Figure 5 is a cross sectional view taken on the line 5—5 of Figure 2;

Figure 6 is a view illustrating an arch gage in connection with a shoe;

Figure 7 is an enlarged detail elevation partly in section, and

Figure 8 is a sectional view taken on the line 8—8 of Figure 7.

Referring specifically to the drawings, a base is provided as at 10, partly along the sides of which, are risers 11. At one end of the base 10, a housing 12 is built. Removably disposed on the base 10 between the risers 11 is an adjustable arch-imprinting device generally designated 13. Rigidly mounted in housing 12 is a shaft 14 about which a roller 15 is adapted to revolve and a clock spring 16 is interposed between the

shaft 14 and roller 15, having its terminals respectively connected to them. An absorbent ink pad 17 is carried on the periphery of roller 15. A belt or tape 18 has one end as 60 at 19 fastened to the roller 15. The spring 16 is so arranged and tensioned that it normally urges rotation of the roller 15 so as to retract the tape 18 and wrap it about the pad 17 so that the moist ink thereon will be 65 transferred to the pad. The tape or belt 18 passes from the housing under and against a roller 20 which is journaled on and carried by a vertically adjustable guide plate 21. Said plate 21 is positioned between guide 70 strips 22 located at the front of the housing. Spring fingers 23 are fastened to the top of the guide plate 21 and have lugs 24 adapted to engage the outer surfaces of the risers or sides 11, for instance recesses 25 in the latter, 75 so as to hold the plate 21 at different elevations and thereby govern the elevation of the roller 20 and adjacent portion of the belt 18. Surplus ink is scraped from the surface of the tape or belt 18 by a fixed 80 scraper 26 located within the housing.

The forward end of the inking belt or tape 18 is detachably connected to a generally U-shaped bail 27 which is pivoted at its terminals 28 as in clamps or ears 29 fastened to the sides 11. To effect a separable connection between said belt 18 and the bail 27, the belt at its distal end is preferably connected to a rigid or metallic plate as at 28 which has a depending hook 29a adapted 85 to engage the bridge of said bail.

Referring specifically to the device 13, it may have a suitable stop as at 30 centrally and longitudinally of which a rod 31 is disposed. This rod is held against longitudinal 90 movement but is rotatable in a bearing 32 fixed to the stop 30. Said rod 31 has screw threads as at 33, 34 and 35. The screw threads 33 are right hand screw threads while those at 34 and 35 are left hand screw 95 threads. Slides 36, 37 and 38 are suitably mounted in the stop for longitudinal movement and are threaded to the respective screw threads 33, 34 and 35. Said screw threads are of such pitch, preferably, so as 100 through turning of rod 31 they will simultaneously travel to different extents and for instance slide 36 will move one and one-sixteenth inches, while slide 37 will travel one and one-fourth inches and slide 38 move 105 one and one-half inches.

An arch is formed on the stop 30 and for

2
instance by spaced arcuate plates 39 joined together by rivets at 40 which have central screw threaded openings engaged by the threads of thumb screws 41. A bracket 42 is rigidly fastened to the slide 37 and rotatably carries the screws 41 as shown. Adjacent each corner and at the sides, the plates 39 are joined by clamps or clips 43 fastened thereto. Slidably disposed partly intermediate said plates 39 and at opposite ends thereof are arcuate plates 44. Said plates 44 and 45 overlap flat plates 46 and 47 respectively. Plates 46 and 47 are respectively fastened to the bearing 32 and to the slide 38. The plate 47, thus being movable with the rod 31 and plate 46 remains fixed. Fastened to the slide 36 is a plate 48 which is movable with said slide and overlapped by the plate 46. Plate 48 has a heel guide 49 pivoted at one end thereof as at 50 and has its other end in the form of a spring finger 51 adapted for separable connection with a stud or the like 52 on the heel guide 49 to normally hold the latter in its usual position. The belt guide is raised with respect to the plate 48 so that the belt or tape 18 may pass therethrough. Vertically slidably centrally of the heel guide 49 is a marker 53. The hinge mounting of the heel guide 49 enables the same to be raised so as to disengage the belt or tape 18 when the latter is disengaged from the bail 27 preparatory to removing the device 13. The tape 18 is of such length that the same, as shown in Figure 1, will not be completely drawn into the housing 12.

The plates 46 and 47 are cut away at their upper surfaces as at 55 to provide seats for the outer ends of the plates 44 and 45 and shoulders 56 against which said plates abut. Also arcuate bolts or other fastenings 57 extend rigidly from the plates 44 and 45 through openings in the plates 46 and 47 and into enlarged openings 58 in the base of the arch imprinting device. Below said plates 46 and 47, expansive springs 59 surround the bolts 57 and abut the plates 46 and 47 and removable nuts 60 on said bolts 57.

50 In using the apparatus, with the device 13 in place on the base 10 and with the belt 18 fastened to bail 27, such bail 27 is thrown forwardly so as to dispose the belt relatively close to and over the various plates on the stop 30. The foot from which an imprint is to be taken, is then placed with the heel against the guide 49 with the foot resting on the plate so that the imprint, particularly of the metatarsal point will be imprinted on the plate by the ink on the under surface of tape 18 and which is applied thereto by the ink of pad 17 while the tape is wrapped about the same. The rod 31 is turnable or adjustable so as to vary the length of the device or position relatively of the plates

lengthwise and the thumb screws 41 are turnable so as to vary the height of the arch or central portion of the plate 39. The imprint will be directly on the different plates, 48, 46, 44, 39, 45 and 47 but if preferred, a sheet of paper may be placed over such plates and directly receive the imprint. The marker 53 is adapted for depression against the belting 18 to make an imprint of the rear end or line of engagement of the heel with the guide 49.

In case an imprint is to be taken and it is preferred not to use the arch, the device 13 is bodily removable from the base 10 by detaching the belt 18 at 29 and swinging the heel guide 49 to open position to release the same. When the device 13 is removed, the belt guide 21 is preferably depressed or lowered so as to bring the adjacent portion of the inking tape 18 closer to the base 10. A sheet of paper or the like is preferably placed on the base 10 between the sides 11 after which the belt 18 is pulled forwardly to cover the same and the foot is placed directly on the tape or belt. The imprint will appear on the paper as understood.

The plates 39, 44 and 45 are preferably resilient.

A gage, as shown in Figure 6 is preferably used to facilitate the determination of the height of the arch of the shoe. Such a gage is shown in use in Figure 6 and within a shoe. It may consist of a plurality of blades 60, each preferably pointed at the shoe engaging ends as shown and each having an elongated slot 61 accommodating a bolt 62 for adjustably fastening the blades together.

Various changes may be resorted to provided they fall within the spirit and scope of the invention.

What is claimed is:—

1. A device of the class described comprising a stop, arch place means on said stop, said means consisting of a plurality of slidably engaging sections, and means to adjust said arch place means vertically and longitudinally.

2. A device of the class described having a stop, an arch place device thereon, said device consisting of a plurality of slidably engaging sections and means operable to adjust the arch place device longitudinally with respect to the stop.

3. A device of the class described having a stop, an arch place device thereon comprising a plurality of slidably engaging plates substantially conforming to the contour of the upper surface of the arch of the shoe, and means operable to adjust said plates relatively to the stop and to one another.

4. A device of the class described having a stop, an arch place device thereon comprising a plurality of slidably engaging plates substantially conforming to the contour of

- the upper surface of the arch of the shoe, other plates engaging said arch place device, means to simultaneously actuate said arch place device plates and the last mentioned 5 plates, and means operable to adjust said plates relatively and to different extents with respect to said actuating means.
5. A device of the class described having a stop, an arch place device thereon comprising a plurality of slidably engaging plates, other plates engaging said arch place device plates, all of said plates conforming substantially to the shape of the upper surface of the shank of the shoe, a threaded rod 10 engaging and providing operating means for said plates, and means to operate said plates to different distances through the same movement of said rod.
15. A device of the class described having a stop, arch plates thereon, other arch plates at the ends of the first mentioned arch plates
- and slidable relatively thereto, other plates engaged by the last mentioned arch plates, means to move one of the last mentioned plates, fastenings extending from the second 25 mentioned arch plates and through the last mentioned plates, and expansive springs on said fastenings.
7. A device of the class described having a stop, a rod journaled on said stop, three 30 slides screw threaded to said rod, a bracket carried by the intermediate slide, plates carried by the other slides, an arch plate adjustably mounted on said bracket, a plate on said bearing overlapping the plate of one of 35 said slides, two of the plates being cut away and providing shoulders, arch plates at the end of the first mentioned arch plates engaging said shoulders, and expansive spring connections between the second mentioned 40 arch plates and adjacent plates.

JOSEPH L. BARTH.
